United States Patent Office.

GEORGE S. HUDSON, OF ELLISBURG, NEW YORK.

Letters Patent No. 65,226, dated May 28, 1867.

IMPROVEMENT IN MOULDING MACHINES.

The Schedule referred to in these Letters Patent and making part of the same.

TO ALL WHOM IT MAY CONCERN:

Be it known that I, GEORGE S. HUDSON, of Ellisburg, in the county of Jefferson, and State of New York, have invented a new and useful Improvement in Machinery for Cutting Wood Mouldings; and I do hereby declare that the following is a full, clear, and exact description thereof, which will enable others skilled in the art to make and use the same, reference being had to the accompanying drawings, forming part of this specification, in which—

Figure 1 is a side elevation of my improved machine for cutting wood mouldings.

Figure 2, a plan or top view.

Figure 3, a front end view.

Similar letters of reference indicate like parts.

This invention relates to improvements in machinery for cutting waved or serpentine wood mouldings, and these improvements consist in a vibratory rotating cutter-head, having bearings in a reciprocating frame, connected with a walking-beam and other suitable mechanism for producing motion, as hereinafter described.

A is a supporting-frame, the general construction of which, together with the gearing, is similar to that of the ordinary straight-moulding machines now in use. B is an adjustable table or side leaf, on which the strip of wood is laid for cutting the moulding *a* in the usual way. The table is raised or lowered, to suit the thickness of the moulding, by vertical screws *b b*, and the moulding is held up against the side of the frame by an adjustable guide-bar, *c*, fig. 2. The feed-rolls *d d* rest in bearings on the top of the framing, taking motion from a pinion, *e*, on the shaft of the pulley *C*, and are adjusted in their pressure upon the moulding strip by a bar, *d'*, fastened to the cap of the bearing *g*, which bar is raised or lowered by a set-screw, *h*. The cutter-shaft *D* has its bearings *i i* in the upper end of a reciprocating frame *E*, and receives motion by the pulley *k* from the large pulley *F* on the main driving-shaft *l* at the rate of four thousand revolutions per minute. The reciprocating frame *E* receives its motion from a walking-beam, *G*, with which it is connected by the pitman *m*, and the reciprocating movement of the frame is made more or less for the purpose of regulating the depth of cut in the mouldings with the cutter-head *z*, by adjusting the walking-beam *G* to work with more or less leverage, which adjustment is effected by shifting the walking-beam in the hub *n*, to which it is secured by the set-screw *n'*. The walking-beam *G* is connected at the other end by the pitman *m'* with a plate-crank, *p*, on the end of the shaft of the cone-pulley *H*, which is belted to the cone-pulley *H'* that takes its motion from the small pulley *F'* on the driving-shaft *l* which carries the fast-and-loose pulleys *F*', which take motion from any suitable power. The pulley *C* that drives the feed-rolls receives motion from a small pulley, *C'*, on the end of the shaft of the cone-pulley *H'*.

The operation of the machine is manifest. The strip of wood to be cut for a moulding is sawed a little across the grain for waving patterns, and with the grain as usual for straight and plain work, to both of which my improved machinery is equally applicable, thus making one machine available for both purposes and all kinds of mouldings, according to its adjustment and the patterns of the cutter-head. By the regular reciprocating movement of the sliding-frame *E* and the adjustment of leverage of the walking-beam *G*, it will be seen that the moulding is cut to any depth required in the wave, and that the longitudinal curve in the wave can be varied in length and character as required.

Having described my invention, I claim as new, and desire to secure by Letters Patent—

The combination of the cutter-shaft *D*, the reciprocating frame *E*, and the walking-beam *G*, or the equivalents of them, or either of them, the said combination being so organized, substantially as described, that by its mode of operation the cutter-shaft *D* and the cutter-head *z* shall rise and fall while in motion to cut any required depth or curve in wave or serpentine wood mouldings.

GEORGE S. HUDSON.
